SPARK PLUG

George M. Paulson, New York, N. Y., assignor to
 The B. G. Corporation, New York, N. Y., a corporation of New York

Application September 12, 1932, Serial No. 632,745

10 Claims. (CL 123—169)

This invention relates to spark-plugs, and more especially to spark-plugs for use in aviation engines.

The object of the invention has been to provide a spark-plug which would give superior, reliable and long service under the conditions to which aviation spark-plugs are subjected, and even when very high compressions, with extreme super-charging, are resorted to.

10 A further object has been to provide an aviation spark-plug which, under most difficult conditions, would not heat up to the point of causing pre-ignition.

15 A further object has been to provide a construction which would protect the core and keep it relatively cool under such conditions.

20 A particular object of the invention is to provide an improved electrode construction or combination which gives the maximum length of service without adjusting or re-setting the gap. A further object is to provide a construction with which it is easy to adjust the gap when it does eventually burn away sufficiently to require re-setting, and which can be re-set repeatedly, for 25 successive long periods of service.

25 Another particular object is to provide the maximum amount of metal to burn away at the gap and a maximum amount of heat conduction to the body or shell of the plug.

30 Another object is to provide a spark-plug having the maximum amount of area of metal at the gap and which can still be easily adjusted.

35 Another object is to provide the maximum amount of metal at the gap with a comparatively small amount of metal exposed to the high cylinder temperatures.

40 Another object is to provide a construction with which there is no danger of longitudinal expansion of the electrode elements closing the gap sufficiently to produce a short circuit.

Still another object is to provide a construction which promotes the flow of gases into and out of the plug.

45 Another object is to provide a construction which is easy and economical to manufacture.

The invention relates to the type of spark-plug having several electrode prongs extending from the body or shell into proximity to a central electrode, and more especially to the kind of 50 construction in which these prongs are cut or formed from a disc or baffle of a metal or alloy which is resistant to the spark in the presence of cylinder gases, this baffle being united to the shell, which is usually of a different metal. The 55 prongs or pronged baffle provide a plurality of

spark gaps, and by partly closing the chamber of the shell, into which the core projects, and by carrying heat off into the shell protect the core from too intense radiant heat and shield it more or less from lubricating oil. The shell electrode 5 should not substantially close the inner end of the core chamber, since a comparatively large orifice area aids in preventing overheating. The construction disclosed herein provides ample orifice area. By properly proportioning the solid 10 area of the baffle or group of prongs, the spaces between the prongs and the amount and distribution of metal in the baffle, and if there be enough heat conduction from the baffle into the shell, it is possible to shield the core sufficiently from 15 temperatures on the order of 2600° F. or higher, and still enable the multiple gap electrode to function satisfactorily and not superheat itself or the plug to a point of failure. The electrode baffle, or the group of prongs, must be heavy in 20 order to stand up and save itself and the core from excessive heating, but not so heavy as to be an accumulator of heat.

In a prior application, now Patent No. 1,959,639, issued May 22, 1934, I have set forth 25 the discovery of the cause of failure of electrode-baffle spark-plugs of ordinary construction when subjected to severe conditions in aviation engines, and a solution of the difficulty, which was to unite the baffle to the shell by a thorough, fused 30 joint. The prior practice was to clamp the edge of the baffle in a groove of the shell by crimping the end of the shell under the baffle, a plan which apparently produced a perfectly solid construction, but which, I became convinced, did permit 35 gases to enter the joint and cause deterioration, reducing the capacity of the shell to draw off heat from the baffle until, after more or less service, the baffle would overheat sufficiently to cause pre-ignition, this in turn causing the sparking 40 points to burn away quickly.

The construction claimed in my former application is embodied in the spark-plug disclosed herein, and is highly important in combination with the present improvements.

45 The other features of this invention relate to the form and relation of a central electrode head and the opposed or surrounding electrode prongs. Briefly, the head of the spindle or central electrode is rather like an inverted truncated cone, 50 with its sides preferably incurved at the spark-gap in axial planes, while the stout prongs, instead of extending radially inward, or in a cupwise manner, from the baffle or shell, are directed inward and steeply downward and preferably on a 55

convex curvature, substantially paralleling the lines of the head. The result is to produce a much deepened or vertically extended multiple spark-gap, with so much metal and surface at the gap that the time over which the plug will perform properly without adjustment is greatly prolonged. The feature of adjustability being preserved, and being easy to utilize, the total life of the plug is extraordinarily increased. In the case of a 10 fusion-bonded baffle construction having these new features, the success of the spark-plugs is due both to the presence of a large amount of metal to burn away very slowly and to a maximum amount of heat conductivity.

15 Other advantages of the invention have already been indicated, and to these should be added the fact that the construction makes possible a spindle head of minimum length.

In the accompanying drawing, illustrating a 20 preferred embodiment of the invention:

Fig. 1 is a view of the spark-plug with the lower part in section and the rest of the plug in elevation; and

Fig. 2 is a bottom plan view looking at the inner end of the plug.

The body or shell of the spark-plug is designated by the reference character 2, and 3 is the central spindle. The spark-plug is preferably and typically of the mica-insulated class. A known construction is shown in which the spindle is surrounded first by a sleeve 4 of rolled mica, this sleeve being compressed against the spindle by means, including a nut 5, to produce a leak-tight dam, and in which a stack 6 of mica washers in 30 the chamber 7 of the plug is held under compression between the head 8 of the spindle and an abutment in the shell, and another stack 9 of mica discs is held under compression between the nut 35 and the top piece 10 over which the upper end of the spindle is upset.

Heretofore the electrode or sparking end of the spindle of a spark-plug has usually been a comparatively narrow cylinder, and in a construction such as illustrated the head or lower portion of 45 the spindle has been rounded inward below the shoulder, with the cylindrical electrode projection extending downward from the convexity.

The spindle head 8 of the spark-plug shown in the drawing is relatively short as compared with 50 a head and pin-like sparking projection such as shown in my Patent No. 1,959,639, for example, and it tapers downward from a broad base to a truncated lower end 11. The precise form may be varied, but the best results are secured by concaving the lines 12 of the sides of the head 45 extensively with the deep spark-gap 13. For the short distance above the gap, the curvature 14 of the head is preferably convex, this reverse curvature being advantageous.

60 The electrode baffle 15 may be understood to be of a nickel-manganese alloy or some other metal or alloy resistant to the spark, and which can be bent repeatedly without injury. It is placed in an open bottom seat in the lower end 65 of the shell or body 2 and is secured in place by a fused bond 16 as in my patent aforesaid. This bond may be made by welding or brazing, the latter bond, which involves a third metal, being 70 adequate to resist the heat and insuring perfect heat conductivity as between the baffle and the shell, and at the present time being more convenient for production purposes than welding.

This disc and its set of sparking prongs 26 are 75 of considerable thickness, a thickness on the order

of .080" being sufficient (this being given by way of example). The prongs are of substantial width and are preferably three or more in number (four being very satisfactory), symmetrically disposed about the center. The openings 17 between the 5 prongs are relatively large. In the end view of the plug the prongs appear to be substantially radial, but seen in vertical section they turn downward quite precipitously, bringing their blunt end faces even with the end face 11 of the 10 head and their sloping inner side surfaces 19 into opposition to the sides 12 of the head across the spark-gap 13. The prong surfaces 19 are preferably convexly curved in axial planes on a curvature substantially corresponding to that of 15 the lines 12 of the head, so that the spacing is virtually uniform throughout a gap of very considerable depth.

In planes at right angles to the axis of the 20 plug the sparking surfaces of the prongs are concavely curved, as seen in Fig. 2, concentrically with the cross-sectional circularity of the head.

An electrode baffle made of a separate piece from the body 2 and bonded in a virtually integral manner therewith is most advantageous for the 25 purposes of the invention, but in some instances the baffle or the prongs may be in one piece with the shell, and obviously the improvements may be applied to the mechanically locked or crimp-lock type of baffle construction, with advantages 30 as compared with prior practice but with considerable sacrifice of benefits as compared with the preferred embodiment of this invention.

While a spark-plug constructed in accordance with my invention has been described in detail it 35 will be understood that various changes may be made without departing from essentials.

I claim:

1. A spark-plug having a shell, a downwardly tapering central electrode, and a set of massive 40 prongs united with the lower end of the shell and constituting ground electrodes, said ground electrodes extending inward from the shell and being directed steeply downward around the central electrode and so formed that their inner side 45 surfaces substantially follow the lines of the sides of the central electrode, so that there is a deep and large spark gap surface area between the central and ground electrodes, with a large section in the ground electrodes to carry off heat 50 into the shell, the ground electrodes being adjustable by deflecting their downturned portions inwardly, so that in such adjustment the large spark gap surface area may be maintained, said ground electrodes being formed in a baffle which 55 is cut out between the prongs, the periphery of said baffle being united to the shell by a fused, heat-conducting bond.

2. A spark-plug having a shell, a downwardly and concavely tapered central electrode, and a 60 set of stout prongs united with the lower end of the shell and constituting ground electrodes, said ground electrodes extending inward from the shell and being directed steeply downward in a convex curvature and having broad inner surfaces which substantially follow the curvature of the central electrode, the formation of said ground electrodes and their relation to the central electrode being such that there is a large spark gap surface area between the central elec- 65 trode and the ground electrodes.

3. A spark-plug having a shell, a downwardly and concavely tapered central electrode, and a set of stout prongs united with the lower end of the shell and constituting ground electrodes, said 70

5 ground electrodes extending inward from the shell and being directed steeply downward in a convex curvature which substantially follows the curvature of the central electrode, the formation 10 of said ground electrodes and their relation to the central electrodes being such that there is a large spark gap surface area between the central electrode and the ground electrodes, the inner side surfaces of said prongs being convexly 15 curved in axial planes and concavely curved in transverse planes.

10 4. A spark plug having a shell, a central electrode with a substantially cone shaped head and a set of massive prongs united with the lower end 15 of the shell and constituting ground electrodes, inner side surfaces of the said prongs conforming to the shape of the center electrode head, so that there is a deep and large spark gap surface area 20 between the center and ground electrodes, which said gap may easily and accurately be measured by a narrow strip or wire gauge feelers, with a large section in the ground electrodes to carry off heat into the shell, the ground electrodes being adjustable by deflecting their down turned 25 portions inward, so that in such adjustment the large spark gap surface area may be maintained.

30 5. A spark plug having a shell, a downwardly and substantially uniformly tapering center electrode head and a set of prongs united with the lower end of the shell constituting the ground 35 electrodes, said ground electrodes being flattened and extending inward from the shell and being shaped concentrically around and directed down the tapered center electrode head so as to furnish large surface areas for the spark gap and a large section in the electrodes for conducting heat to the shell, as well as to be flexible enough for adjustment of the gap.

40 6. A spark plug having a shell, a downwardly tapering circular spindle head, and a set of stout ground electrodes supported by the shell and extending inwardly and downwardly therefrom and having inner side surfaces cross-axially curved 45 concentrically with and extending downwardly along the circular spindle head to circumferentially and longitudinally conform thereto and collectively surround the greater part of the circumference of the complementary portion of the spindle head at the gap, so as to furnish a plurality of large surface areas for the spark gap, 50 with a large section in each ground electrode for conducting heat to the shell, said ground electrodes being adjustable by bending them radially of the plug, so that, by such adjustment, the large 55 surface areas for the spark gap may be maintained.

60 7. A spark plug having a shell, a downwardly tapering circular spindle head, and a set of stout ground electrodes supported by the shell and extending inwardly and downwardly therefrom and having inner side surfaces cross-axially curved 65 concentrically with and extending downwardly along the circular spindle head to circumferentially and longitudinally conform thereto, with

at least the lower end portions of said surfaces collectively surrounding the greater part of the circumference of the juxtaposed portion of the spindle head, so as to furnish a plurality of large surface areas for the spark gap, with a large section 5 in each ground electrode for conducting heat to the shell, said ground electrodes being adjustable by bending them radially of the plug so that, by such adjustment, the large surface areas for the spark gap may be maintained.

10 8. A spark plug having a shell, a downwardly tapering circular spindle head, and a set of stout ground electrodes supported by the shell and extending first inwardly and then downwardly therefrom and having, on the downwardly extending portions thereof, inner side surfaces cross-axially curved concentrically with and extending downwardly along the circular spindle head to circumferentially and longitudinally conform thereto, with at least the lower end portions 20 of said surfaces collectively surrounding the greater part of the circumference of the juxtaposed portion of the spindle head, so as to furnish a plurality of large surface areas for the spark gap, with a large section in each ground 25 electrode for conducting heat to the shell, said ground electrodes being adjustable by bending their downwardly extending portions radially of the plug so that, by such adjustment, the large surface areas for the spark gap may be main- 30 tained.

35 9. A spark-plug having a shell, a downwardly tapering central electrode, and a set of massive prongs united with the lower end of the shell and constituting ground electrodes, said ground electrodes extending inward from the shell and being directed steeply downward around the central electrode and so formed that their inner side surfaces substantially follow the lines of the sides of the central electrode, so that there is a deep 40 and large spark gap surface area between the central and ground electrodes, with a large section in the ground electrodes to carry off heat into the shell, the ground electrodes being adjustable by deflecting their downturned portions in- 45 wardly, so that in such adjustment the large spark gap surface area may be maintained, said ground electrodes being formed in a baffle which is cut out between the prongs, the said baffle being supported at its periphery adjacent the lower 50 end of the shell and making good heat-conducting and electrical connection therewith.

55 10. A spark-plug having a shell, a downwardly tapering central electrode head, and a set of prongs united with the lower end of the shell 55 constituting ground electrodes, said ground electrodes extending inward from the shell and being shaped concentrically around and directed down the tapered center electrode head so as to furnish large surface areas for the spark gap, 60 the ground electrodes being likewise of large section for conduction of heat to the shell, yet flexible enough for adjustment of the gap.

GEORGE M. PAULSON.
